UNITED STATES PATENT OFFICE.

JEROME P. KRIMKE, OF NEWARK, NEW JERSEY.

TOY HORSE.

Application filed April 20, 1928. Serial No. 271,529.

This invention relates to a toy hobby horse and it consists in the novel features herein-after described and claimed.

An object of the invention is to provide a hobby horse of the character stated upon which the rider may be seated and by raising and lowering his body, will cause the horse to move over a plane surface and at the same time swing its body so that it will have the appearance of galloping.

A still further object of the invention is to provide in a toy horse of the character stated, simple and efficient means for causing the toy to move in a straight forward direction as indicated, and also means for guiding the toy so that it may be caused to travel in a curved path, if desired.

In the accompanying drawing.

Figure 1 is a side elevational view of the toy horse.

Figure 2 is a plan view thereof.

Figure 3 is a section on the line 3—3 of Figure 1.

Figure 4 is a section on the line 4—4 of Figure 2.

Figure 5 is a section on the line 5—5 of Figure 2.

Figure 6 is a modification of my improved toy horse showing a front view of my horse with four legs.

As illustrated in the accompanying drawing, the toy includes a body 1, representing a horse in the act of galloping. The body 1 is provided at that portion thereof representing the head and mouth of the animal with a handle 2 which may be used by the rider of the toy for maintaining poise upon the toy when the same is in movement as will be hereinafter explained. A saddle 3 is pivoted at one end upon the body of the animal above the front shoulders thereof, and the free end portion of the said saddle is disposed over the intermediate portion of the back of the animal.

A lever 4 is fulcrumed at a point between its ends to the intermediate portion of the body of the animal and approximately transversely of the spine thereof. The power end of the lever 4 projects above the upper side of the back of the animal and is provided with freely journalled rollers 5 which bear upon the under surface of the saddle 3. A spring or springs 6 are connected at one end with the intermediate portion of the lever 4 and at their other ends with the hind legs of the animal. The said springs

6 are traction springs and serve to hold the lever 4 at a normal position whererby the rollers 5 are projected above the upper side of the back of the animal and the rear end of the saddle 3 is normally held at an elevated position. The lower portion of the lever 4 is forwardly disposed as at 7 and one end of an angular bracket 8 is pivoted to the under side of the said portion 7. A bar 9 is pivoted to the under end of the bracket 8. The point of pivotal connection between the bar 9 and the bracket 8 is at a right angle to the pivot which connects the bracket 8 with the forward portion 7 of the lever, and consequently, the bar 9 may have universal swinging movement with relation to the lever. The bar 9 may serve as a foot rest for the rider and by turning or twisting the bar with relation to the body of the animal, the toy may be steered or guided over the surface of a floor as will be hereinafter explained.

An axle shaft 10 is journalled upon the bar 9 and carries at its ends supporting wheels 11. A ratchet wheel 12 is fixed to the intermediate portion of the shaft 10 and a pawl 13 is pivoted upon the bar 9 at its free end engages the teeth of the ratchet wheel 12 at the upper side thereof. The said ratchet wheel and pawl are so arranged and disposed that the axle 10 may turn over at its upper side in a forward direction, but the upper portion of the axle cannot turn rearwardly.

A block 14 is carried at the ends of the hind leg of the figure represented by the body 1 and an axle shaft 15 is journalled upon the block 14. Supporting wheels 16 are carried at the ends of the shaft 15. A ratchet wheel 17 is mounted upon the intermediate portion of the axle 15 and a spring pressed pawl 18 is pivoted upon the block 14 and bears upon the upper side of the ratchet wheel 17. The ratchet wheel 17 and the pawl 18 are so arranged and assembled that the shaft 15 is held against turning over rearwardly but the said shaft 15 may turn over in a forward direction.

When the rider is seated upon the saddle 3 and uses the cross bar 9 as a support for his feet the rider may work his body vertically and thus the seat or saddle will rise and fall and inasmuch as the saddle engages the power end of the lever 4, the said lever will be rocked or swung with relation to the body 1. At the same time, the body 1 is

caused to rise and fall as its forward end, thus giving the body of the toy the appearance of galloping. As the forward portion of the body 1 descends with relation to the bar 9 and axle shaft 10, the wheels 11 turn over forwardly and are spread away from the wheels 16. When the body 1 rises, the wheels 11 are held at rest upon the floor surface and the wheels 16 turn over and approach the wheels 11. This causes the body of the toy to have the appearance of moving over a floor surface and of galloping while the body of the rider reciprocates vertically with relation to the path of movement over which the toy travels.

In Figure 6, I have shown a modified form of my toy horse, showing a body 20 having fore legs 21 attached thereto. The rear legs 22 are attached to the rear block. 20 This form of my invention is formed with a heavier animal body and shows that the four legs may be formed on my device instead of the form shown in Figures 1 and 2, if so desired.

25 From the foregoing description of the construction and operation of this improved device, it will be seen that a simple, inexpensive and efficient means is provided for carrying out the objects of the invention.

30 While I have particularly described the elements best adapted to perform the functions set forth, it is obvious that various changes in form, proportion and in the minor details of construction may be resorted to, without departing from the spirit or sacrificing any of the principles of the invention.

Having described the invention, what is claimed is:

- 40 1. A toy comprising a body simulating that of an animal, a saddle pivoted upon the body, a lever fulcrumed upon the body and having one end frictionally engaging the saddle, an axle pivotally connected with the lower end of the lever, wheels carried by said axle, a ratchet wheel mounted upon the axle, a pawl pivotally supported with relation to the lever and engaging said ratchet wheel, an axle journalled at the rear portion of the body, wheels carried by the last mentioned axle, a ratchet wheel carried by the last mentioned axle and a pawl pivotally

mounted with relation to the body and engaging the last mentioned ratchet wheel.

2. A toy comprising a body simulating an animal, a handle mounted at the forward end thereof, a saddle pivoted upon the body, a lever fulcrumed upon the body and having a power end engaging under the saddle, spring means for normally holding the working end of the lever rearwardly with relation to the body, an axle, pivotally mounted at the working end of the lever, supporting wheels carried by said axle, a ratchet wheel mounted upon the axle, a pawl pivotally mounted with relation to the lever and engaging said ratchet wheel, an axle journalled at the rear end of the body, supporting wheels carried by the last mentioned axle, a ratchet wheel carried by the last mentioned axle and a spring pressed pawl pivoted with relation to the body and engaging the last mentioned ratchet wheel.

3. A toy comprising a body, a saddle member pivoted thereon, a lever fulcrumed thereon and having a power end engaging under the saddle, spring means secured to the body and lever for normally holding the power end of the lever at an elevated position, a bar pivotally connected with the lever and adapted to serve as a foot rest, an axle journalled upon the bar, wheels carried by said axle, means mounted on said axle for holding said axle against reverse movement, an axle journalled at the rear portion of the body, 80 wheels carried by the last mentioned axle and means on the last mentioned axle for holding the same against reverse movement.

4. A toy comprising a body, a saddle pivoted thereon, a lever fulcrumed upon the body and engaging the saddle, a bracket pivoted to the lever, a cross bar pivoted to the bracket, and adapted to serve as a foot rest, an axle journalled upon the bar, wheels carried by the axle, means on said axle 95 for holding said axle against reverse movement, an axle journalled at the rear portion of the body, wheels carried by the last mentioned axle and means on the last mentioned axle for holding the same against reverse 100 movement.

In testimony whereof I affix my signature.

JEROME P. KRIMKE.
